ATTORNEYS

UNITED STATES PATENT OFFICE.

JOHN CHRISTIAN ST. CLAIR, OF BUTTE, MONTANA.

COMBINED COAL STOKER AND BURNER.

Application filed April 11, 1927. Serial No. 182,890.

This invention relates to a combined coal stoker and burner, the primary object of the invention forming the subject matter of this application being to provide means whereby air is forced downwardly upon the fuel in the fire box, the fuel being fed to the box or the burning area thereof through the medium of an automatically reciprocated stoker.

10 This application is directed to an improvement on the apparatus constituting the subject matter of my original application filed July 22, 1925, patent issued June 21, 1927, and given Patent Number 1,633,465.

15 With this and other objects in view, the invention consists in certain novel features of construction and combinations and arrangements of parts which will be more fully hereinafter described and pointed out in the 20 claim.

In the accompanying drawings—

Figure 1 is a plan view of my improved apparatus showing one form of air-directing means such as illustrated in the apparatus 25 of my original application;

Figure 2 is a view in vertical section and at right angles to Figure 1;

Figure 3 is a perspective view of the stoker box and air-directing flue;

30 Figure 4 is a view, similar to Figure 3 but partly in section, illustrating a modification;

Figure 5 is a plan view, partly in section, of the structure shown in Figure 4.

1 represents a table or support which may 35 be adjustable vertically and is preferably portable and which supports a fire box 2 adapted to be projected through an opening 3 in a furnace 4.

The fire box 2 has a hopper 5 at its outer 40 end through which fine fuel 6 may be directed into the path of a reciprocating stoker 7 to feed the same longitudinally of the fire box 2.

The stoker 7 is connected by a link 8 with 45 an outlet crank disk 9 on a shaft 10 supported on the table 1, and 11 is a blower also mounted on the table 1 and having a discharge flue 12 with an outlet nozzle 13 located above the fire box and provided with orifices 14 through which the air is directed downwardly onto the fuel in the fire box.

This flue 12 and nozzle 13 are illustrated in Figures 1, 2 and 3 and are of angular form in cross section which is the form illustrated 50 in my original application above referred to.

However, in constructing this flue and nozzle, I preferably employ a form of device such as illustrated in Figures 4 and 5. In this form of the device the air flue 14, corresponding to flue 12, may be in circular form 60 and has a swivel gooseneck nozzle 15 at its end which may be positioned over the fire box to discharge the air downwardly therein, or may be swung to one side, as occasion may require.

65 The flue 14 has an opening 16 therein communicating with an opening 17 in the side wall of the fire box 2 so as to allow a certain amount of air to enter the fire box and keep the fuel back of the point of combustion relatively cool.

70 The air blower 11 and the shaft 10 may both be driven by a single motor 18 through the medium of gearing 19 with a gear box 20 on table 1, and the electric circuit to the motor 18 may be controlled by a thermostat 21 located wherever desired to give the best results.

75 Various changes and alterations might be made in the general form of the parts described without departing from the invention and hence I do not limit myself to the precise details set forth but consider myself at liberty to make such changes and alterations as fairly fall within the spirit and 80 scope of the appended claim.

I claim:

In a device of the character described, a hollow body extending into an opening in a side wall of the furnace casing, said hollow 90 body constituting a fire box portion within the furnace casing, a fuel supply chamber outside of the furnace open at its upper end at the outer side of the furnace casing and a fuel feeding passage extending through the 95 opening in the wall of said furnace casing and extending between said fire box and said fuel chamber, a plunger reciprocable in the lower part of the fuel supply chamber and in said fuel feeding passage for delivering 100 fuel from said fuel supply chamber to said fire box and an air delivery conduit extending alongside of said body into said furnace casing and having a nozzle portion supported above said fire box, said discharge nozzle 105 having rows of spaced discharge apertures in its lower part located in position to discharge air blasts downwardly and outwardly onto fuel within said fire box.

JOHN CHRISTIAN ST. CLAIR.
